United States Patent Office

Des. 234,266
Patented Feb. 4, 1975

234,266

POINT OF SALE TERMINAL

Alfonso W. Merino, Edward J. Sabella, and Roger C. Williams, Raleigh, N.C., assignors to International Business Machines Corporation, Armonk, N.Y.

Filed June 13, 1973, Ser. No. 369,617

Term of patent 14 years

Int. Cl. D14—02; D20—02
U.S. Cl. D52—4 A

FIG. I

FIG. 2

FIG. 3

FIG. 4

FIG. 5

FIG. 6

FIG. 7

FIG. 1 is a front, left side and top perspective of a point of sale terminal showing our new design;

FIG. 2 is a right side, top and rear perspective view thereof;

FIG. 3 is a rear elevational view thereof;

FIG. 4 is a top plan view thereof;

FIG. 5 is a front elevational view thereof;

FIG. 6 is a right side elevational view thereof; and

FIG. 7 is a left side elevational view thereof.

We claim:

The ornamental design for a point of sale terminal, as shown.
